US0D1041447S

(12) **United States Design Patent** (10) **Patent No.:** **US D1,041,447 S**
(45) **Date of Patent:** **** Sep. 10, 2024**

(54) **EAR TIPS COVER**

(71) Applicant: **Shenzhen Zhengzhongba Technology Co., Ltd.**, Shenzhen (CN)

(72) Inventor: **Shaokai Yang**, Shantou (CN)

(73) Assignee: **Shenzhen Zhengzhongba Technology Co., Ltd.**, Shenzhen (CN)

(**) Term: **15 Years**

(21) Appl. No.: **29/933,034**

(22) Filed: **Mar. 18, 2024**

(51) LOC (14) Cl. **14-01**

(52) U.S. Cl.

USPC **D14/205**

Primary Examiner — Paula Allen Greene

(57) **CLAIM**

The ornamental design for an ear tips cover, as shown and described.

DESCRIPTION

FIG. 1 is a front perspective view of an ear tips cover, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the ear tips cover, which form no part of the claimed design.

1 Claim, 8 Drawing Sheets
